(57) **CLAIM**

The ornamental design for an electronic humidifier and heater, as shown and described.

DESCRIPTION

FIG. 1 is a top front and left side perspective view of electronic humidifier and heater showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

The broken line showing of parts of the drawings is included for the purpose of illustrating use and environment and forms no part of the claimed design.
